United States Patent Office.

JAMES M. KEEP, OF NEW YORK, N. Y.

Letters Patent No. 103,752, dated May 31, 1870.

IMPROVED TWINE-HOLDER.

The Schedule referred to in these Letters Patent and making part of the same

To all whom it may concern:

Be it known that I, JAMES M. KEEP, of New York city, in the county of New York and in the State of New York, have invented a new and useful Improvement in Twine-holders; and do hereby declare that the following is a full, clear, and exact description thereof, reference being had to the accompanying drawing making a part of this specification, in which—

Figure 1 is a side elevation of my improved device, and

Figures 2, 3, and 4, are vertical central sections of the cover, body, and base, respectively, of the same.

Letters of like name and kind refer to like parts in each of the figures.

My invention is an improvement in cases or holders for containing balls of twine, and

It consists in constructing the twine-holder with a cast-metal cover and base, and a sheet-metal body, as is hereinafter set forth.

Heretofore, twine-holders have been constructed entirely of cast metal, or of sheet metal spun into the desired form, with the base and body formed of one piece, by which means it was found impracticable to furnish the completed article at a reasonable cost, as, in case cast metal was employed, great difficulty was experienced in producing a body having an equal thickness and free from imperfections, while by the use of sheet metal, great labor and expense were necessary in forming the holder.

To obviate these objections, I construct my holder with a cast-metal cover and base, A and B, respectively, and a sheet-metal body, C, said base being provided with a suitable flange, b, over which the lower end of the body is fitted, and said parts secured to-

gether by means of rivets passing horizontally through the same.

The cover A is also provided with a flange, a, which corresponds with and fits into the upper end of the body C, and holds the former firmly in place.

The cover and base may, however, have any form deemed best, although I prefer those shown in the drawing, while the body may be either solid or cut into an open-work pattern, so as to increase its beauty without materially decreasing its strength.

The especial advantages possessed by this method of constructing the holder, are,

First, it materially decreases the cost of the same, as the parts can be more easily and cheaply constructed separately, and then combined, and

Second, it enables manufacturers to furnish sheet iron workers in small places with the cast portions of the holders, to which may be added at any time a body having such style and consisting of such material as is desired.

Having thus fully set forth the nature and merits of my invention,

What I claim as new, and desire to secure by Letters Patent, is—

As a new article of manufacture, a twine-box or holder having its cover and base constructed of cast metal, and its body of sheet metal, substantially as shown and described.

In testimony that I claim the foregoing, I have hereunto set my hand this 23d day of April, 1870.

J. M. KEEP.
